DESK SET

Herbert C. Schulze, 3690 Highland Drive,
Carlsbad, Calif. 92008

Substituted for abandoned design application Ser. No. 260,
Dec. 21, 1965. This application June 22, 1967, Ser. No.
8,938

Term of patent 14 years

(Cl. D74—5)

FIG. 1 is an exploded perspective view of a desk set showing my new design;

FIG. 2 is a side elevational view;

FIG. 3 is an end elevational view looking from the left of FIG. 2;

FIG. 4 is an end elevational view looking from the right of FIG. 2; and

FIG. 5 is a bottom plan view thereof.

This is a substitute for my abandoned application Ser. No. D-260 filed on Dec. 21, 1965.

I claim:

The ornamental design for a desk set, substantially as shown and described.
